US00D988449S

(12) **United States Design Patent** (10) **Patent No.:** **US D988,449 S**
(45) **Date of Patent:** **** Jun. 6, 2023**

(54) **GOLF CLUB HEAD**

- (71) Applicant: **PARSONS XTREME GOLF, LLC**,
Scottsdale, AZ (US)
- (72) Inventors: **Robert R. Parsons**, Scottsdale, AZ
(US); **Michael R. Nicolette**, Scottsdale,
AZ (US); **Bradley D. Schweigert**, Cave
Creek, AZ (US)
- (73) Assignee: **PARSONS XTREME GOLF, LLC**,
Scottsdale, AZ (US)
- (**) Term: **15 Years**
- (21) Appl. No.: **29/883,956**
- (22) Filed: **Feb. 6, 2023**

Related U.S. Application Data

- (63) Continuation-in-part of application No. 29/855,738,
filed on Oct. 6, 2022, which is a continuation-in-part
of application No. 29/841,818, filed on Jun. 8, 2022,
now Pat. No. Des. 980,360.

(57) **CLAIM**

The ornamental design for a golf club head, as shown and
described.

DESCRIPTION

FIG. 1 is a top perspective view of a golf club head
according to a first embodiment;
FIG. 2 is a bottom perspective view of the golf club head of
FIG. 1;
FIG. 3 is a rear elevational view of the golf club head of FIG.
1;
FIG. 4 is a front elevational view of the golf club head of FIG.
1;
FIG. 5 is a top view of the golf club head of FIG. 1;
FIG. 6 is a bottom view of the golf club head of FIG. 1;
FIG. 7 is a left side view of the golf club head of FIG. 1;
FIG. 8 is a right side view of the golf club head of FIG. 1;
FIG. 9 is a top perspective view of a golf club head
according to a second embodiment;
FIG. 10 is a bottom perspective view of the golf club head
of FIG. 9;
FIG. 11 is a rear elevational view of the golf club head of
FIG. 9;
FIG. 12 is a front elevational view of the golf club head of
FIG. 9;
FIG. 13 is a top view of the golf club head of FIG. 9;
FIG. 14 is a bottom view of the golf club head of FIG. 9;
FIG. 15 is a left side view of the golf club head of FIG. 9;
and,
FIG. 16 is a right side view of the golf club head of FIG. 9.
The broken lines shown on the drawings form no part of the
claimed design.

1 Claim, 8 Drawing Sheets
